UNITED STATES PATENT OFFICE.

WENDELL CARTER AND HENRY T. WOODS, OF BOSTON, MASSACHUSETTS.

CAR-COUPING.

SPECIFICATION forming part of Letters Patent No. 286,175, dated October 9, 1883.

Application filed April 6, 1883. (No model.)

To all whom it may concern:

Be it known that we, WENDELL CARTER and HENRY T. WOODS, of Boston, in the county of Suffolk, State of Massachusetts, have invented a certain new and useful Improvement in Car-Couplers, of which the following is a description sufficiently full, clear, and exact to enable any person skilled in the art or science to which said invention appertains to make to and use the same, reference being had to the accompanying drawings, forming a part of this specification, in which—

Figure 1 is an isometrical perspective view representing our improved coupler in use; Fig. 2, a perspective view of a draw-bar head with the link removed; Fig. 3, a vertical longitudinal section of the same; Fig. 4, a vertical longitudinal section, showing the buffer extended and link elevated; and Fig. 5, a view of the link detached.

Like letters of reference indicate corresponding parts in the different figures of the drawings.

Our invention relates to that class of car-couplers which are automatic or self-coupling; and it consists in a novel construction and arrangement of the parts, as hereinafter more fully set forth and claimed, by which a more effective device of this character is produced than is now in ordinary use.

The nature and operation of the improvement will be readily understood by all conversant with such matters from the following explanation, its extreme simplicity rendering an elaborate description unnecessary.

In the drawings, A B represent the cars, C D the draw-bar heads, and W the link. The draw-bars are attached to the cars and provided with springs at their inner ends in the usual manner. The draw-bar head C is mortised longitudinally, and fitted to slide therein is a buffer-bar, H, provided with a head, E, at its outer end, and with a coiled spring, J, at its inner end, the spring acting expansively to force the bar out of the mortise. A lateral slot, K, is formed in the top of the head, this slot opening downwardly into the mortise in which the bar H slides, and being elongated or cut out at its base, as shown at x, to form the inwardly-projecting hooks L M. These hooks have their inner ends cut out, as shown

at a, and there is also a concavity formed in the upper side of each, as shown at m.

Projecting upwardly from the bar H into the mortise h there is a hook, N, and immediately in front of this hook the bar is provided with an elongated depression or cavity in its upper side, as shown at P. A curved notch, f, is also formed in the top of the bar H, behind the hook N, and beyond this there is a vertical slot, g, passing entirely through the bar.

At the rear of the hook L there is a vertical mortise, O, extending from the top of the head C into the mortise in which the buffer-bar H works, and pivoted therein is a lever, R, provided with a laterally-projecting shoulder, n. A pawl, S, is pivoted conjointly with the lever R in the mortise O, the lower end of the pawl extending into the notch f and engaging the bar H. A hole, T, provided with the coupling-pin U, is formed in the draw-bar head at the rear of the mortise O, this hole being adapted to register with the slot g in the bar H. A hole, v, is also formed in the forward end of the bar H, designed to receive a coupling-pin, (not shown,) and said bar is mortised longitudinally at h, to receive an ordinary coupling-link. The link W having each of its ends curved or bent downwardly at the center, as shown at i, and inwardly, as shown at j, (see Fig. 5) is employed for connecting the draw-bar heads.

In the use of our improvement, the link W being in the slots K, with the curved portions i projecting downwardly into the cavity P, and the bars H pushed in to nearly their fullest extent and held by the pawls S, if it is desired to uncouple the cars they are backed or run together, bringing the buffer-heads E E into contact, pushing the bars H in to their fullest extent and causing the ends of the link W to pass in under the hooks L. The chain Y, connecting with the lever R, is then pulled upwardly by the brakeman on the car A, bringing the shoulder n against the upper end of the pawl S, disengaging said pawl from the bar H, and permitting the spring J to force said bar forward and cause the hook N to engage the curved portion i of the link. The car A is then slowly started forward, withdrawing the hook L of the head C from the

link, and permitting the spring J in the head D to expand and force the bar H forward to its fullest extent, causing the hook N to engage the curved portion *i* on the end of the link in the head D. As the car A advances and releases the link W from the hook L of the head C, the hook N on the bar H in the head D acting on the curved portion *i* of the link will force it forward into a cavity, *l*, beneath the hook M, thereby causing the link to be thrown out of the slot K in the head C and elevated, as shown in Fig. 4, in which position it will be securely fastened and carried as the car A travels. The link being in the head D in the position shown in Fig. 4, with the buffer-bar extended, if, now, it is desired to connect the cars again, the chain Y is lowered and the car A backed until its buffer is struck by the buffer of car B and forced in sufficiently to permit its pawl S to fall into the notch *f*, when the link, being released by the hook which has kept it elevated, will fall into the notch K in the head C and couple the cars, in a manner which will be readily understood without a more explicit description.

It will be understood that each of the draw-bar heads is precisely like the other, and therefore, that the description given of the head C applies well to D; also, that the method described for detaching the car A from the car B applies equally well when it is required to detach car B from car A.

The coupling-pin U is connected to the chain Y by a branch chain, *z*, and hook *b*, the branch chain being of such a length that when the main chain Y is drawn up the pin will be withdrawn from the slot *g* and permit the bar H to be forced forward by its spring.

For the purpose of coupling a car fitted with our improved draw-bar head, buffer, and link to a car of the ordinary construction, the buffer-bars are mortised, as shown at *h*, to receive the ordinary link, which is secured by a coupling-pin inserted in the hole *v*, the outer ends of the draw-bar heads C D being vertically grooved, as shown at *I*, to receive one side of the pin and prevent it from jamming between the buffer-head E and draw-bar head. The curved portion *i* forms a crank, with which the hook N engages as the bar H is forced forward by the spring J, thereby journaling the end of the link between the hooks N M and causing its free end to pass through the arc of a circle of which *x* is the center. The concavities *m* and curves *a* are for catching and guiding the curved portion *i* into the cavity P as the elevated end of the link falls in coupling the cars. The object of bending the curved portions *i* inwardly, as shown at *j* in Fig. 5, is to prevent the link from being elevated at too great an angle by the hook N when forced under the hook M. When the link is elevated and buffer extended, as shown in Fig. 4, if the cars are backed together until the buffer in the head D strikes the buffer in the head C, the link will drop as the buffer-bar is pushed in and the

curve *i* on the free or outer end of the link will fall into the concavity *m* in the hook L of the head C. The link being thereby stopped from advancing, the end in the head D will slide backward in the slot K as the cars approach each other until the buffer-bar is locked by its pawl S and the cars are moved apart, when the end of the link which rests in the cavity *m* of the hook L in the head C will fall into the slot K. When both buffer-bars are retracted and locked by their pawls, the cars are backed together as far as possible, the ends of the link will pass under the hook L, and as the cars are separated will engage the hooks M, as shown in Fig. 1. The buffers E perform all of the functions of ordinary buffers, and their bars remain withdrawn or in their respective draw-bar heads until released by pulling on the chains Y. The chain *z* is of such a length and so arranged that when the chain Y is pulled up to unlock the bar H the pin U will be drawn entirely out of the slot *g*, but not entirely out of the draw-bar head, its point being left in the hole *T*, and when the chain Y is lowered to permit the pawl S to engage the bar H the pin U will pass into and partially through the slot *g*, so that in case the pawl becomes accidentally thrown out of the notch *f* the bar H cannot be withdrawn from the draw-bar head.

When the cars are coupled by an ordinary link inserted in the mortise or mouth *h*, the chain *z* is lowered on the chain Y by the hook *b*, so that the pin U will pass through the hole *T* and slot *g*, or entirely through the draw-bar head and buffer-bar H, and the chain Y drawn up to disengage the pawl from the notch *f*, thus bringing all of the strain on the pin U. When both of the buffer-bars H are extended and the link elevated, as shown in Fig. 4, if the cars are brought together for the purpose of coupling, the free or elevated end of the link as it falls will strike in the concavity *m* of the hook M in the opposite draw-bar head, (instead of the cavity *m* in the hook L, as when but one buffer-bar is extended,) and will slide down said cavity and be guided into the slot K as the cars come together. The upper side of the hook M on each of the heads is rounded or conical, so that the link will pass readily down over it in coupling the cars.

Having thus explained our invention, what we claim is—

1. The improved car-coupler herein described, the same consisting of the draw-bar heads C D, each provided with the hooks L M, lever R, pawl S, and hole T, the bars H, provided with a buffer, E, cavity P, hook N, notch *f*, slot *g*, spring J, hole *v*, and mortise *h*, in combination with the link W, chains Y *z* *z*, and pins U U, constructed, combined, and arranged to operate substantially as set forth.

2. In a car-coupler, the link W, provided with the curves or cranks *i* *i*, in combination with the hooks N and means for elevating one

end of said link to uncouple the car, substantially as described.

3. In a car-coupler, the link W, having the curves or cranks *i i* inclined inwardly to prevent the link from being raised too high by the hook N, substantially as described.

4. In a car-coupler, the hook M, provided with the concavity *m* to receive the curve *i* on the link W and guide the link into the slot K, substantially as described.

5. In a car-coupler, the concavity *m* in the hook L, for receiving the curve *i* on the link W and guiding the link into the slot K, substantially as specified.

15 6. In a car-coupler, the draw-bar head D, provided with the buffer-bar H, in combination with means for locking said buffer-bar within the head, and a spring for forcing it out, substantially as set forth.

20 7. In a car-coupler, the cavity P in the bar H, to receive the curve *i* of the link W, substantially as shown and described.

8. In a car-coupler, the cavity *l* beneath the hook M, to receive the hook N and curve *i* when the bar H is forced forward to elevate the link W, substantially as specified.

25 9. In a car-coupler, the bar H, provided with the mortise or mouth *h*, hole *v*, slot *g*, spring J, and pin U, in combination with the head D, substantially as set forth.

10. In a car-coupler, the chain Y, in combination with the lever R, pawl S, and bar H, substantially as and for the purpose specified.

30 11. In a car-coupler, the chain Y, provided with the branch chain *z*, in combination with

the pin U, lever R, pawl S, and bar H, substantially as set forth.

12. In a car-coupler, the head C, provided with the vertical groove *l⁵*, to prevent the pin in the hole *v* from jamming between the buffer E and said head, substantially as shown and described.

13. In a car-coupler, the curve *a* in the hook M, to permit the inwardly-inclined curve *i* of the link W to pass readily into and out of the slot K, substantially as set forth.

14. In a car-coupler, the lever R, provided with the shoulder *n*, in combination with the pawl S, substantially as and for the purpose specified.

15. In a car-coupler, a draw-bar head carrying a sliding buffer-bar, the buffer-bar being provided with means for engaging the coupling-link and elevating one end of the same to uncouple the cars, substantially as set forth.

16. In a car-coupler, the combination of the following instrumentalities, to wit: a draw-bar head provided with a hook for engaging the coupling-link, a spring-buffer bar carrying a buffer and fitted to slide longitudinally in the draw-bar head, means for locking the buffer-bar in the draw-bar head, and means for elevating the coupling-link or detaching it from one of the draw-bar heads with which it is engaged, substantially as described.
